UNITED STATES PATENT OFFICE

JOHN WESLEY DENNIS, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA

AUTOMATIC CARRIER-TURNING MECHANISM FOR DRYING MACHINES

Application filed October 31, 1927. Serial No. 229,926.

This invention relates generally to drying machines and, more particularly, to the types through which article-carriers are automatically progressed, by means of a rotary slotted-platen, with provision for periodic "entry" and "exit", relative to the drying zone, to effect application and removal of the articles treated.

More specifically the present improvements aim to provide a novel conveying mechanism, for machines of the typified character, which is automatically instrumental to effect uniform directional alignment of the article-carriers for entry into, progress about, and exit from the drying zone of the machine. As a result, the operations of "boarding" and "stripping" clothing-carriers, for instance, are more expeditiously carried out; while the general efficiency of drying machines, equipped with this invention, is greatly enhanced; and, incidentally economy in overhead expense, by saving of time and labor, effected.

Heretofore the means common to carry out the operations above stated have usually embodied cams cooperative with stationary obstructions, or the equivalents thereof; and, in contradistinction therewith, my invention essentially embraces a combination of mechanically operated studs, rollers and trip-fingers, which jointly impart a "positive" turning movement to the article-carriers.

For a clearer understanding of my invention, as well as to fully appreciate the aims and advantages thereof, reference is made to the accompanying sheets of drawings; which, when considered in conjunction with the following detailed explanation, serve to disclose a practical adaptation thereof; whereas, the subjoined claims tersely recite the alleged features of novelty.

In the drawings, corresponding parts are distinguished by like reference characters throughout the several views.

Fig. I is a sectional plan through an automatic hosiery-dryer incorporating my improvements, and taken approximately on the plane indicated by the arrowed line I—I in Fig. II.

Fig. II is a staggered vertical section as

viewed approximately in the direction indicated by the line II—II in Fig. I.

Fig. III is a fragmentary plan view in section of my novel mechanism operative to effect uniform directional alignment of successive article-carriers for proper entering into—and progress about—the drying zone of the machine.

Fig. IV is an elevation of the preceding view.

Fig. V is a plan view in section—similar to Fig. III—of the means employed to effect directional movement of the article-carriers on leaving the drying zone of the machine;

Fig. VI is a broken elevation looking toward the upper hand of the preceding illustration.

Referring first to Figs. I and II, it will be seen that the typified adaptation of my invention illustrated comprises an enclosure 7, of thermo-insulated sheets 8 and standard sections 9, with a bellied frontal portion 10, all supported at an elevation above floor level by a substructure 11. The enclosure 7 is subdivided by a vertical partition 12 to define a space 13 for conventional heating means—not shown. Transversely of the space 13 is an inwardly-convergent rectangular-section air-inlet 14 communicating into the casing collar 15 of a vertically rotatable fan 16, connected by a belt drive 17 with a suitable motor 18, braced to the back of the machine by a skeleton support 19, in an obvious manner.

The vertical partition 12 is fitted with a lateral baffle 20 having a frontal canopy 21 which defines the drying zone 22; while said baffle and canopy are located above a slotted-platen 23, that "closes-in" the hollow head 24 of a rotary pedestal 25. This pedestal 25 is revolvable by a vertical shaft 26, and it is supported over a gear box 27 which houses the mechanism instrumental to reciprocate a "selector" or pusher-bar 28, through the medium of a shaft 29, co-ordinated with the fan shaft 30 by a belt-drive 31, or other appropriate driving mechanism. The means adapted to intermittently actuate the pusher-bar 28 is of any approved type, and is not

illustrated herein as it does not constitute a part of the present invention.

Each article or form-carrier 32, is removably—or otherwise—supported by a holder 33 having a toothed shank 34 co-operative with the correspondingly toothed socket 35 of a bearing bracket 36, through aid of an axial-stem 37, secured in said shank by a cotter-pin 38; and said bracket is rigidly attached to the outer end of a thrust-bar 39 adapted for radial manipulation in the hollow pedestal head 24. Each thrust-bar 39 is provided with notches 40, 41 at its lower edge for engagement with a cupped flange 42 about the gear box 27.

All of the foregoing matters do not constitute features of the present invention but are illustrated—and briefly explained—as essential to a correct understanding of the improvements now to be described in detail; viz, the means effective to automatically turn the article or form-carriers 32 into proper alignment, for correct entry into—and ejection from—the drying zone 22, of the machine.

In the drawings I have shown my invention as adapted to an "automatic hosiery dryer" in which the form-carriers 32 are progressed about the drying zone 22—toc 30 inwards, with a counter-clockwise or left-hand directional travel, while said carriers enter and leave the machine enclosure 7 by way of vertical slots 43, 44,—Fig. I—respectively.

Referring now, more particularly, to Figs. III and IV, which illustrate the mechanism at the carrier-entering side of the machine, it will be seen that the selector or pusher-bar 28 is formed, or otherwise provided, 40 with a plate-head 45, fitted with "turning" or upstanding studs 46, 47; a "draw" or actuator-stud 48; and what I term a rocker-arm stud 49. These several studs are of any conventional type adapted for rigid securement in the plate-head 45, and their respective functions will be, later on, fully explained. The rocker-arm stud 49 is headed for non-releasable cooperation with the slot 50 of a rocker-arm 51, pivoted on a stud 52 rigidly fixed in a bearing plate 53, conveniently supported by bracings 54, 55, to the machine sub-structure 11, in an obvious manner. This rocker-arm 51 is provided, at its pivotal end, with a lateral ear or side lug 56, to which is fulcrumed—by a pin 57—one end of a connecting rod 58, the other end of said rod being similarly attached at 59 to the shorter arm 60 of a crank member, freely pivoted on a stud 61, secured in the bearing plate 53, aforesaid. On the longer arm 62, of the crank member just referred to, there is mounted a roller 63 that is freely rotatable about a fixed axis 64, said roller being adapted to engage the wing portion 65 of a block 66, rigidly attached to the lower end

of the article or form-carrier axial-stem 37, hereinbefore referred to; while a spring 67 is interposed between said block and the lower end of the bearing socket 35, to keep the parts 34, 35 in mutual engagement.

The following will briefly explain the manner in which the just described mechanisms co-operate. Assuming, an article or form-carrier 32 to be approaching the entry slot 43, along the dot-and-dash course O. C.—Fig. III; with the heel of the form 68 inwards and, conveniently, conforming alignedly with the longitudinal median of the wing 65 as shown at *a*; while the roller 63 occupies the position shown by dotted lines. It will now be readily understood that, as the form 68 commences to advance in the direction of the arrow, or counter-clockwise, it will be automatically turned about its axis to the position shown at *b* for proper entry into the machine enclosure 7 through the entry slot 43. Further progress of the form-carrier 32 in the just stated direction, with concurrent movement outwards of the pusher-bar 28 results in the stud 47 engaging the obtuse angled side of the block wing portion 65, which imparts a further turn to the form-carrier 32 into the position marked *c*, for correct entry into the drying zone 22. Should a form carrier 32, however, pass along the course O. C. as in 7 toe-foremost, then the actuation of the 7 to-foremost, then the actuation of the pusher-bar 28 advances the stud 46 into contact with the notched out side 69 of the wing 65, and thereby turns said form carrier to the directional position designated *c*, aforesaid. It will, of course, be well understood that the "turning" studs 46, 47 are positionally located, on the plate-head 45, to 95 positively effect the turning movements of the form-carrier 32, just explained.

On the return stroke or inward reciprocation of the pusher-bar 28, the relatively shorter or actuator-stud 48 engages the rectangular lower portion of the block 66, and thereby pulls the carrier 32, and sustained form 68, into the drying zone 22 for progress thereabout over the course designated I. C., the prescribed number of times; whereupon it will be ejected by way of the exit slot 44, through the medium of the mechanism now to be explained.

Referring now, more particularly, to Figs. V and VI it will be seen that the pusher-bar 28 is formed—or fitted—with a cam-path 70 and an opposed lateral ear or side lug 71, bearing a vertically directed actuator stud 72. Immediately below the pusher-bar 28, and securely fastened to the sub-structure 11 of the machine is a plate 73, on which is located a crank member 74 free to turn about a stationary axis or stud 75. On the shorter arm 76 of the crank member 74 there is mounted a roller 77 free to rotate about a 130

fixed axis 78, while the longer arm 79 of said crank member is connected at 80 to a connecting rod 81, the other extremity whereof is similarly joined at 82 to one arm 83 of a rocker 84, freely pivoted to an axis or stud 85, fixedly mounted on the plate 73, aforesaid. The other arm 86 of the rocker 84 is coupled by a universal-connector 87 to one end of a connecting-rod 88, the other end whereof is similarly coupled by a corresponding-connector 89 to the vertically directed finger 90 of a trip device 91, freely pivoted on a bearer stud 92 secured to a plate 93, made fast in the machine sub-structure or framework 11. The trip device 91 is fitted with a crank arm 94 and adjustable counter-weight 95; while it is to be particularly noted that the connecting rod 88 is screw-threaded into both universal connectors 87, 89; so that ample provision is afforded for varying the "throw" of the several mechanical elements thereby co-ordinated.

The manner of operation of the just described mechanism is briefly as follows. Assuming a form-carrier 32 has reached the position marked *e*—Fig. V—with the pusher-bar 28 at the "in" position relative thereto, it will be readily understood that, on the next outward movement of said bar, the actuator stud 72 will engage the block 66, and move or draw the carrier 32 from its inner path of travel I. C., to the outer course O. C., along which it continues to advance, in the direction of the arrow, to the position designated *f*. At this point the pusher-bar 28, on its return—or inward—stroke, draws the inclined edge 96, of the cam plate 70 into—and over—the roller 77, which causes the crank member 74 to swing about its axis 75 from the full-line to the dotted-line position. As a result motion is transmitted by the connecting rod 81 to the rocker 84, which in turn imparts a reverse directional-pull upon the universally-jointed connecting rod 88, thereby swinging the trip device 91 upwardly upon its axis 92. Consequently, the trip finger 90 is brought into contact with the obtuse-angled or "follower" edge 97 of the block winged position 65, thereby turning the form carrier 32 into the directional position indicated at *g*—or toe foremost. On release of the finger 90 from engagement with the wing 65, it will be obvious that the counter-weight 95 returns the co-ordinated mechanical elements back to the full line position of Fig. V, ready for the next operative cycle, while the form 68 is moved out through the exit slot 44, in the manner hereinbefore explained.

In order to eliminate any possibility of the operator endeavoring to turn a form 68 in the wrong direction while passing exteriorly or in front of the machine during the operations of "stripping" and "re-clothing," and incidentally causing damage to the

goods and operating mechanism, I make use of a guard rail 98—Fig. V—that is supported by the combined table and humidifier 99 in such location as to prevent the successive form-carriers 32 being turned in a clockwise direction, but permits of the individual ones being given a half-turn counter-clockwise on its axial stem 37 from the position shown at *g*.

From the foregoing it will be apparent that the proper and correct alignment of the forms 68 for progress about the drying zone 22, as well as their directional turning is automatically obtained by means of the respective studs 46, 47 and 48, actuator stud 72, rollers 63 and 77, and the trip finger 90, which effect "positive" movements, all as hereinbefore set forth.

Finally, it is thought that the simple and practical phases embraced in the illustrated embodiment of my invention will be clearly appreciated; and that it is designed to accomplish all of the objects set forth in a positive manner; while I reserve the right to make such variations therein as are fairly comprehended within the meaning and range of equivalency circumscribed by reasonable interpretation accorded the following claims.

Having thus described my invention, I claim:

1. In a drying machine including a rotary platen sustaining radially-thrustable article-carriers, the combination of an intermittently reciprocative member adapted by direct action to correctly align the individual carriers for predetermined positional entry into, progress about, and ejection from the machine.

2. In a drying machine including an enclosure and a rotary platen sustaining radially-thrustable article-carriers, the combination of an intermittently-reciprocative member adapted by direct action to correctly align the individual carriers for entry into, progress about, as well as ejection from the enclosure, and mechanism directly operated by the reciprocative member effective to turn successive carriers for positional advancement into and out of said enclosure.

3. In a drying machine including an enclosure and a rotary platen sustaining radially-thrustable article-carriers, the combination of an intermittently-reciprocative member having terminal protrusions adapted by direct action to correctly align the individual carriers for movement relative to the rotary platen, and mechanisms directly operated by the reciprocative member to turn successive carriers for movement into and out of the enclosure aforesaid.

4. In a drying machine including an enclosure and a rotary platen sustaining radially-thrustable article-carriers, the combination of an intermittently-reciprocative

- member having terminal protrusions adapted by direct contact to correctly align the individual carriers for movement relative to the rotary platen, mechanism operatively coupled with the reciprocative member to turn successive carriers for entry into the enclosure, and mechanism directly activated by said member serving to similarly turn the carriers for ejection therefrom.
5. In a drying machine including an enclosure and a rotary platen sustaining radially-thrustable article-carriers, the combination of an intermittently-reciprocative bar having end projections, crank and rocker mechanisms operative by one of the projections at each end of said bar to positively turn the article-carriers into entering and ejective direction respectively, others of the projections operating by direct contact to correctly align said carriers for movement into—progress around—and ejection from the enclosure, and the remaining projections adapted to thrust said carriers radially of the platen aforesaid.
10. 6. In a drying machine including an enclosure and a rotary platen with radial thrust-bars having form-carriers pivoted to the outer ends thereof, the combination of an intermittently-reciprocative bar having 70 75 80 85 90 95 100 105 110 115 120 125 130 positionally located studs at one end for direct co-action with a laterally winged block on each carrier pivot, one of said studs being operatively coupled to a crank and rocker mechanism functional to turn the individual carriers into enclosure-entering direction, a plurality of said studs respectively engageable against opposed sides of the carrier with respect to its pivot when alignedly advancing—or in a rightabout—direction to correctly turn such carrier for radial location during progress about said enclosure, another of said studs serving to thrust the carrier radially inward to enclosure progressive location, and mechanism directly activated by projections at the other end of the reciprocative bar correspondingly moving successive carriers into ejective directional location.
7. In a drying machine including an enclosure and a rotary platen with radial thrust-bars having form carriers pivoted to the outer ends thereof, the combination of an intermittently-reciprocative bar having 100 105 110 115 120 125 130 positionally located studs at one end, one of which is coupled to a crank and rocker mechanism operative to turn the individual carriers into enclosure-entering direction, other of the projections functioning by direct contact to correctly align the carriers for movement into and progress around the enclosure, and the remaining projection adapted to thrust the carriers radially of the platen aforesaid.
40. 8. In a drying machine including an enclosure and a rotary platen with radial thrust-bars having form-carriers pivoted to the outer ends thereof, the combination of an intermittently-reciprocative bar having 70 75 80 85 90 95 100 105 110 115 120 125 130 positionally located studs at one end adapted by co-ordination and direct-action to respectively turn successive form-carriers into enclosure entering-and-progressive directional alignment, a stud and a cam path at the other end of the reciprocative bar, the former of which serves to thrust the carrier from enclosure progressing to ejective position, and the latter adapted to activate a crank and rocker mechanism operative to turn the article-carrier into proper ejective alignment.
45. 9. In a drying machine including an enclosure and a rotary platen with radial thrust-bars having form-carriers pivoted to the outer ends thereof, the combination of an intermittently-reciprocative bar having 100 105 110 115 120 125 130 positionally placed studs at one end adapted by co-ordination and direct-action to respectively turn successive form-carriers into enclosure entering-and-progressive directional alignment, a stud and a cam path at the other end of the reciprocative bar, the former of which serves to thrust the carrier from enclosure-progressing to ejective position, and the latter adapted to activate a crank and rocker mechanism operative to turn the article-carrier into proper ejective alignment.
50. 10. In a drying machine including an enclosure and a rotary platen with radial thrust-bars having form-carriers pivoted to the outer ends thereof, the combination of an intermittently-reciprocative bar having 100 105 110 115 120 125 130 positionally placed studs at one end adapted by co-ordination and direct-action to respectively turn successive form-carriers into enclosure entering-and-progressive directional alignment, a stud and a cam path at the other end of the reciprocative bar, the former of which serves to thrust the carrier from enclosure-progressing to ejective position, and the latter adapted to activate a crank and rocker mechanism operative to turn the article-carrier into proper ejective alignment.
55. 11. In a drying machine including an enclosure and a rotary platen with radial thrust-bars having form-carriers pivoted to the outer ends thereof, the combination of an intermittently-reciprocative bar having 100 105 110 115 120 125 130 positionally placed studs at one end adapted by co-ordination and direct-action to respectively turn successive form-carriers into enclosure entering-and-progressive directional alignment, a stud and a cam path at the other end of the reciprocative bar, the former of which serves to thrust the carrier from enclosure-progressing to ejective position, and the latter adapted to activate a crank and rocker mechanism co-ordinated

by an universal connection with a trip device operative to turn the article-carrier into proper ejective alignment.

12. In a drying machine including an enclosure and a rotary platen with radial thrust-bars having form-carriers pivoted to the outer ends thereof, the combination of an intermittently-reciprocative bar having positionally placed studs at one end adapted by co-ordination and direct-action to respectively turn successive form-carriers into enclosure entering-and-progressive directional alignment, a stud and a cam path at the other end of the reciprocative bar, the former of which serves to thrust the carrier from enclosure-progressing to ejective position, and the latter adapted to activate a crank and rocker mechanism co-ordinated by an universal connection with a vertically-acting counterweighted trip device operative to turn the article-carrier into proper ejective alignment.

15 In testimony whereof I have hereunto signed my name at Philadelphia, Pennsylvania, this 26th day of October, 1927.

25 JOHN WESLEY DENNIS.
